AUTOMATIC CARBINE

George F. Grebey, Portsmouth, R. I.

Application January 28, 1947, Serial No. 724,740

6 Claims. (Cl. 89—184)

1

The present invention relates to an automatic carbine, especially designed for sporting use, an object of the invention being to provide a carbine type firearm of relatively light weight and high power in which standard pistol or other suitable ammunition may be effectually used. The ammunition may for instance be .357 Magnum pistol ammunition.

It is particularly proposed to provide a firearm of relatively streamline design which will be free of movable projecting parts, such as the bolt lever employed in certain types of firearms, and which will also be free of exposed openings in which mud or dirt may collect and affect the mechanical functioning of the firearm, and in particular in which the cartridge ejecting opening will be sealed in the closed position of the bolt. To this end it is proposed to provide openings in the receiver and in the bolt retracting slide, which register in the retracted position of the slide to permit the cartridge to be ejected, and which are in offset sealed relation in the projected position of the slide. Another object is to provide a bolt adapted to have rectilinear closing and opening movement without rotary movement, and which effectually eliminates firing jam, such as is often evident in firearms utilizing the rotating bolt method.

Another object is to provide effective means for preventing premature firing, and to this end it is proposed to provide a hammer lock mechanism, which is in positive locking relation at all times except when the bolt is in its closed locked position ready for firing, the releasing of the hammer lock mechanism being controlled by direct action of the bolt as the latter is moved into its locking position.

Another object is to provide hammer, trigger and firing mechanism parts contained in a sealed unit which may be quickly and conveniently installed or removed, thus enabling the user of the firearm to readily replace the unit, in the field if necessary, should such parts become damaged or worn. A further object is to provide a repeater type firearm which is readily adapted for either manual opening or pump action of the bolt, or automatic opening. In the case of automatic opening, it is proposed to provide a barrel attachment in the form of an improved gas accumulator, it being proposed to provide in such accumulator a series of gas accumulator chambers coaxial with the bore of the barrel and through which corrosion is eliminated to a great extent and muzzle blast is reduced, thereby silencing the firearm to a substantial degree.

With the above and other objects in view, an

2

embodiment of the invention is shown in the accompanying drawings, and this embodiment will be hereinafter more fully described with reference thereto, and the invention will be finally pointed out in the claims.

In the drawings:

Fig. 1 is the top plan view of the automatic carbine, according to the illustrated exemplary embodiment of the invention.

10 Fig. 2 is a side elevation thereof, a portion of the stock being shown in vertical section.

Fig. 3 is a transverse vertical sectional view, taken along the line 3—3 of Fig. 2.

15 Fig. 4 is a longitudinal vertical sectional view, taken along the line 4—4 of Fig. 1.

Fig. 5 is a fragmentary view, partially in side elevation and partially in vertical section, showing the gas accumulator attachment for automatic opening of the bolt.

20 Fig. 6 is a side elevation of the receiver and barrel group or assembly.

Fig. 6-A is a view, partially in side elevation and partially in longitudinal vertical section, showing the construction of the barrel.

25 Fig. 6-B is a transverse sectional view, taken along the line 6-B—6-B of Fig. 6-A.

Fig. 7 is a side elevation of the upper hand guard member.

Fig. 8 is a side elevation of the lower stock member.

30 Fig. 9 is a side elevation of the bolt.

Fig. 10 is a front end view of the bolt, on an enlarged scale.

Fig. 11 is a side elevation of the hammer, trigger and firing mechanism unit.

35 Fig. 12 is a side elevation of the slide unit for retracting the bolt.

Fig. 13 is a top plan view of the slide.

Fig. 14 is a front end view of the slide.

Fig. 15 is a transverse vertical sectional view, taken along the line 15—15 of Fig. 12.

40 Fig. 16 is a side elevation of the cartridge clip.

Fig. 17 is a front elevation thereof.

Fig. 18 is a detailed fragmentary view, on an enlarged scale, showing the hammer, trigger and firing mechanism in its position ready for firing, and showing the bolt in its projected and locked position.

45 Fig. 19 is a longitudinal horizontal sectional view, taken along the line 19—19 of Fig. 18.

50 Fig. 20 is a transverse vertical sectional view, taken along the line 20—20 of Fig. 18.

Fig. 21 is a side elevation of the body portion of the casing for the hammer, trigger and firing mechanism parts.

55 Fig. 22 is an end view thereof.

Fig. 23 is a plan view thereof.
 Fig. 24 is a side elevation of the cover plate of the casing.
 Fig. 25 is an end view thereof.
 Fig. 26 is a top plan view thereof.
 Fig. 27 is a side elevation of the trigger guard.
 Fig. 28 is a top plan view thereof.
 Fig. 29 is a side view of the trigger spring.
 Fig. 29a is a top view of the trigger spring.
 Fig. 30 is a side view of the sear member.
 Fig. 30a is a front view of the sear member.
 Fig. 31 is a side view of the trigger member.
 Fig. 31a is a front view of the trigger member.
 Fig. 32 is a side view of the trigger control bar member.

Fig. 32a is a top view of the trigger control bar member.

Fig. 33 is a side view of the hammer locking lever member.

Fig. 33a is a top view of the hammer-locking lever member.

Fig. 34 is a side view of the safety latch bar member.

Fig. 34a is a top view of the safety latch bar member.

Fig. 35 is a side view of the safety latch bar operating lever.

Fig. 35a is a front view of the safety latch bar operating lever.

Fig. 36 is a view partially in side elevation and partially in vertical section, showing the hammer, trigger and firing mechanism in its fired position, the bolt being shown in longitudinal vertical section, and the firing pin being shown driven forward by the hammer.

Fig. 37 is a view, partially in side elevation and partially in vertical section, and with parts broken away, showing the slide and the bolt in their fully retracted and open position with the hammer moved to its cocking position and with the cartridge ejection openings of the receiver and slide in registering relation.

Similar reference characters indicate corresponding parts throughout the several figures of the drawings.

Referring to the drawings, the firearm, according to the illustrated exemplary embodiment of the invention, comprises a receiver and barrel group or assembly, shown disassembled from the firearm in Fig. 6, the receiver part 10 having the barrel part 11 connected thereto by a threaded connection 12, the barrel part being provided at its end adjacent the receiver part with a downwardly extending lug 13, of substantially rectangular form, secured to the forward end of the receiver part by means of a filister head screw 14. A guide tube 15 for the recoil spring, herein-after more fully referred to, is secured in a pocket 16 in the lug 13 by means of a pin 17.

The receiver part is of substantially semi-cylindrical form along its upper external surface and is provided internally with a bolt receiving guide channel 18 having vertical side walls and a horizontal top wall, thus forming a channel of substantially rectangular cross-section for guiding the substantially square bolt, as will presently more fully appear. The channel opens downwardly for receiving the hammer and trigger unit and the cartridge clip unit, the side walls of the receiver being extended downwardly for this purpose and having a transverse wall portion 19 dividing the hammer, trigger and firing mechanism unit receiving portion, defined by a slot opening 20, and the cartridge clip receiving portion, defined by a slot opening 21, the forward wall of

5 this latter slot opening being formed by the forward closed end of the receiver disposed directly below the threaded connection 12.

In the upper portion of the receiver there is provided in one side wall substantially in line with the slot opening 21, a cartridge ejection opening 22 and rearwardly of this ejection opening there are provided in the opposed side walls guide slots 23-23 for the bolt. At the rearward end of the receiver part, there is provided a downwardly inclined lug 24 for attaching the stock, as will hereinafter more fully appear. A rear sight unit 25, of any suitable type, is mounted upon the upper side of the rearward end of the receiver part and the front sight unit 26, of any suitable type, is mounted upon the forward end of the barrel.

The bolt, indicated generally as 27, and shown in disassembled relation in Figs. 9 and 10 and in plan and sectional views in Figs. 19 and 36, comprises a rearward portion 28 of substantially square cross-section and a forward portion 29 of substantially cylindrical cross-section, the lower side of the portion 29, however, being at a slight angle to the lower side of the portion 28 and to the upper side of the entire length of the bolt, which is parallel to the underside of the portion 28. Thus, in the forwardly moved closed and locked position of the bolt, as shown in Fig. 36, the underside of the portion 29 is parallel to the axis of the barrel, while the upper surface of the bolt and the lower side of the portion 28 are at a downwardly inclined angle thereto, while, in the open position of the bolt, its upper surface and the lower surface of the portion 28 are parallel to the axis of the barrel, and to the guide channel 18 of the receiver, as shown in Fig. 37.

A firing pin rod 30, having a firing pin 31 at its forward end, is engaged in a guide passage 32 in the bolt, the axis of this passage being coaxial with the axis of the barrel in the forward closed and locked position of the bolt, as shown in Fig. 36. The firing pin 31 is engaged in a reduced diameter forward end portion 33 of the passage, a spring 34 being provided about the firing pin between the forward end of the firing pin rod and the forward end of the passage 32 to exert retracting force thereon, the projecting and retracting movement of the firing pin being limited by a set screw 35 engaged in a notch 36 provided in the firing pin rod. A transverse pin 37 is engaged through a passage 38 in the bolt, as shown in Fig. 20, and is secured by set screws 39-39, a notch 40 being formed centrally in the pin to provide a clearance space for the firing pin rod. The ends of this pin 37 project at each side of the bolt outwardly through the guide slots 23 of the receiver and are adapted to be engaged with the action slide member to control the locking and unlocking movement of the bolt, as will hereinafter more fully appear.

At the forward end of the bolt there is provided a forwardly projected semi-circular rim 41 adapted to position the base of the cartridge, and at the outer side of the forward end there is secured in a recess 42 by means of a screw 43 an extractor tooth member 44 which engages within the extractor groove of the cartridge. At the opposed inner side of the bolt there is provided a slot 45 extending substantially the full length of the portion 39 and terminating in an upwardly extending entrance portion 46. This slot is engaged by an ejector pin 47 screwed in the channel 18 of the receiver, and adapted as the bolt reaches its open position to engage the base of the

cartridge, held at its opposed side by the extractor tooth, to cause the cartridge to swing outwardly through the ejection opening 32. The slot 45 is disposed parallel to the upper side of the bolt 29 so that in the open position of the bolt, as shown in Fig. 37, it is parallel to the axis of the barrel. At the rearward end of the bolt and at its underside there is provided a lug 48 for actuating the hammer locking mechanism, as will hereinafter more fully appear.

The hammer, trigger and firing mechanism assembly unit includes a casing consisting of a body member 49, shown in Fig. 21, and a cover member 50 shown in Fig. 24, the cover member being secured to the casing member by filister head screws 51. The mechanism contained in the casing will be hereinafter more fully described, but, for convenience in description, the form of the casing and its assembly with the receiver will be described at this point. The casing is of substantially rectangular form and is adapted to slide upwardly in the slot opening 20 of the receiver, where it is secured by transverse pins 52 and 53 engaged through holes 54 in the side walls of the receiver and holes 55 in the body and cover portions of the casing. The upper side of the casing is formed by an upper wall portion 56 of the body portion, which is provided at its rearward end with an upwardly extending projection 57 fitting within the rearward end of the bolt channel 18, the upper side of this wall, forwardly of the projection 57, extending in horizontal relation, as at 58, to an intermediate locking abutment 59 with which the rearward end of the bolt is adapted to lock, the upper surface of the case forwardly from this step being inclined upwardly, as at 60, so as to support the bolt in its closed and locked position, as shown in Fig. 18. The vertical distance between the horizontal upper surface 58 of the casing and the upper horizontal wall of the bolt channel 18 corresponds to the vertical dimension of the substantially square rearward portion 28 of the bolt, so that in the raised open position of the bolt, the latter has rectilinear sliding movement between these horizontal surfaces of the channel and the casing.

The upper wall 56 of the casing is provided along the horizontal portion 58 with a hammer slot opening 61 and along the inclined portion 60 adjacent to the abutment 59 with a slot opening 62 in which the lug 48 of the bolt engages in the locked position as shown in Fig. 18. A clearance groove 63 for the lug 48 is provided between the abutment 59 and the slot 61.

An action slide, shown in detail in Figs. 12 to 15, is assembled for rectilinear sliding movement upon the receiver and barrel, and consists of an upper elongated yoke member 64, of inverted U-shape in cross-section, having a pair of forwardly extending arms 65-65, to the forward ends of which there is secured a lower compression head member 66, of trough-like form. The head member is provided at its rearward end with recessed ears 67-67, in which the forward ends of the arms 65 are engaged and secured by screws 68. The yoke member is provided at suitably spaced points along the interior of each of its side walls with inwardly offset downwardly extending guide lugs 69, while the head member is provided with inwardly extending rearward guide lugs 70-70 and forward guide lugs 71-71, the guide lugs of the head member being in a horizontal plane which is upwardly offset with 75

respect to the horizontal plane of the guide lugs of the yoke member.

The receiver is provided at its sides with longitudinal guide slots 72-72 for sliding engagement of the guide lugs 69 of the yoke member, longitudinal ledge portions 73-73 being provided outwardly of the slots for sliding support of the lower edges of the yoke member. The barrel is provided at each side with longitudinal grooved guide rails 75-75 for sliding engagement of the guide lugs 70 and 71 of the head member, the guide rails being in a horizontal plane which is upwardly offset with respect to the horizontal plane of the guide slots 72. The action slide is assembled with the receiver and barrel assembly by engaging it thereon from the forward end and sliding it rearwardly, the guide lugs 69 of the yoke member being first engaged in the forward open ends of the guide slots 72 at each side of the lug 13 beneath the upwardly offset guide rails 75 of the barrel, the guide lugs 70 and 71 of the head member being at the same time engaged with the grooved guide rails 75.

The head slide member 66 is provided with a front wall portion 76 in which is secured a guide rod 77 for the forward end of the recoil spring 78, its rearward end being engaged within the tube 15. Knurled pads 79-79 are secured to the arms 65 near their forward ends to provide convenient hand grips for manual retraction of the slide member.

Adjacent to its forward end the yoke slide portion 64 is provided at one side with a cartridge ejecting slot opening 80, which in the forward bolt locking position of the action slide is forwardly offset from the cartridge ejecting opening 22 of the receiver, so that both openings are completely closed and sealed. In the rearward bolt opening position of the action slide, the opening 80 registers with the opening 22, so that the fired cartridge may be ejected there through. A clearance notch 81 is provided at the rearward end of the yoke slide member 64 so as to clear the rear sight 25 in the retracted position.

The side walls of the yoke slide member are provided with transversely opposed enlargements 82-82, each having a circular threaded opening 83 in which is screwed a threaded cam disc 84, fixed in place by a set screw 85, and having at its inner side a cam groove 86 disposed at a 45° angle. The cam grooves of the two opposed cam discs are engaged by the ends of the transverse pin 37 of the bolt, and are adapted to impart vertical swinging movement to the bolt to engage the rearward end of the bolt with the abutment 59 at the completion of the forward bolt closing movement of the action slide, and to swing the bolt upwardly to disengage it from the abutment at the beginning of the rearward bolt opening movement of the action slide. Thus, in the forward position of the action slide and bolt, as seen in Fig. 18, the pin 37 is at the lower ends of the cam slots. As rearward bolt opening force is applied to the action slide, the pin is raised in the cam slots bringing the square end of the rearward end of the bolt into line with the square guide channel of the receiver, the bolt being thereupon moved rectilinearly to the open position shown in Fig. 37. As the action slide moves forwardly under the force of the recoil spring 78, the transverse bolt pin 37 remains in the upper end of the cam slots until the bolt reaches its forward limit of movement, its rearward end at this point being in line with the locking abutment

39, whereupon the continued forward force of the action slide forces the pin downwardly in the cam slots engaging the end of the bolt in locking relation with the abutment. As the locking abutment is directly under the end of the bolt, the bolt is assisted in its locking action to a certain extent by gravity.

While the barrel 11 may be produced by any satisfactory methods, it is preferably constructed, as shown in Figs. 6-A and 6-B, by providing the barrel 11^a as a substantially cylindrical bored and rifled part having a flange 11^b adjacent the receiver engaging thread 12, and which is engaged with a snug and close fit in a sleeve 11^c, upon which the lug 13 and the longitudinal guide rails 15-15 are integrally formed. This construction permits the barrel to be turned for head space adjustment without throwing the guide rails out of alignment with the rest of the action. In practice such adjustment would be made by inserting shim washers on the thread between the barrel and the receiver.

The cartridge clip comprises an elongated rectangular casing 87 having a closure plate 88 at its lower end removably secured by means of lugs 89, and having at its upper end a relatively thickened portion 90 adapted to be inserted within the slot opening 21 of the receiver, this thickened portion preferably having slots 91 cut therein to reduce the weight of the clip. Within the clip there is disposed a follower 92 and a spring 93 to press the cartridges upwardly, so that they feed automatically into the bolt passage of the receiver. Upon the forward side of the casing there is provided a tooth formation 94 which engages in a vertical groove 95 in the forward wall of the slot opening 21, and is adapted to be releasably retained by means of a latch device.

The latch device consists of a cylindrical rod 96 slidably engaged in a cylindrical passage 97 in the receiver and having at its outer end an upwardly projected knurled thumb piece 98 connected to a guide bolt 99 screwed therein and slidably engaged in a passage 100 in the receiver, the head of the bolt being disposed in a pocket 101 at the opposed side of the receiver from the knurled thumb piece to limit the outward movement of the rod 96, outward pressure being exerted thereon by a spring 102 disposed in the passage 97 between the end of the rod and the base of the passage. The rod is provided with a retaining tooth portion 103 which is normally in line with the groove 95 to engage the tooth 94 of the cartridge clip to retain it, this retaining tooth having at its underside an inclined striker face 104 adapted as the clip is inserted to be engaged by the tooth 94 to cam the latch inwardly, whereupon the retaining tooth automatically engages beneath the tooth 94 under the projecting force of the spring 102. Outwardly adjacent the tooth 103, the latch rod is provided with a flat releasing portion 105, adapted to be brought into register with the groove 95 by pressing inwardly upon the thumb piece of the latch, to thus permit the clip to be removed.

The stock 106, formed of walnut or other suitable material, is suitably recessed and slotted so as to enclose the lower portion of the receiver and barrel assembly, and the hammer, trigger and firing mechanism unit, the upper surface of the stock being in a straight horizontal plane, which in the engaged position is substantially in line with the upper surfaces of the ledges 73 of the receiver. The stock is secured by engaging

5 its forward flange end 107 in a grooved stock ferrule 108, secured to the barrel 11 by a retaining pin 109 fitting within a notch 110 in the underside of the barrel. The rearward end of the stock is secured by a screw 111 engaged in the lug 24 of the receiver, which seats in a recess 112 of the stock, the screw being engaged with a nut 113 secured in the stock. An upper hand guard 114, also formed of walnut or other suitable material, has its forward flanged end 115 engaged with the stock ferrule 108 and encloses the upper side of the rearward portion of the barrel, being suitably recessed to engage over the barrel. Slots 116-116 are provided at the sides of the hand guard in which are engaged the knurled hand grip pads 79 of the bolt reTRACTING slide, the knurled surfaces of these pads projecting slightly beyond the side surfaces of the hand guard so that they may be conveniently engaged by the thumb and fingers to retract the slide.

25 The hammer, trigger and firing mechanism is housed and sealed within the casing formed by the body member 49 and the cover member 50, these members being provided with a plurality of suitably positioned registering holes 117 and 118 in which the retaining and pivot pins of the several parts of the mechanism are engaged and retained, preferably by a drive fit in these holes. The trigger guard 119, shown in detail in Figs. 27 and 28, is secured in the casing by means of pins 120 and 121 engaged through holes 122 and 123 in the trigger guard, this guard being provided at its rearward end with a slotted sear pivotting support 124, and at its forward end with a substantially U-shaped trigger spring receiving recess 125.

30 The sear 126, shown in detail in Fig. 30, is pivotally mounted in the slotted support 124 of the trigger guard by means of a pin 127 engaging a hole 128 in the sear, and is normally pressed in counter-clockwise direction by a helical spring 129 disposed in a pocket 130 of the trigger guard and engaged with a pin 131 provided at the underside of the sear. The sear is provided at its upper rearward corner with the hammer engaging tooth portion 132, and at its upper forward corner with a pivoted tooth pawl 133 normally pressed in clockwise direction by means of a spring 134.

35 The hammer 135 is pivotally mounted in the casing by means of a pin 136, and is normally pressed in clockwise direction by a spring rod 137, seated at its forward end in a pocket 138 of the hammer, and having engaged thereon a helical spring 139, disposed between a shoulder 140 of the rod and the apertured wall portion 141 of the casing through which the rearward end of the rod is slidably engaged. An abutment shoulder 142 is provided upon the forward side of the hub portion of the hammer for engagement by the sear in the cocked position of the hammer, as shown in Fig. 18. The sear is adapted to automatically engage the abutment shoulder under the pressure of the spring 129, as the hammer is moved, through the opening movement of the bolt, from its firing position, as shown in Figure 36, to its cocking position, as shown in Fig. 37, the opening movement of the bolt causing the lug 48 of the bolt to force the hammer slightly beyond its cocked position so that the sear falls into place in front of the abutment shoulder, the forward movement of the bolt allowing the hammer to thereupon move into its cocked position, as shown in Fig. 18.

The trigger 143, shown in detail in Fig. 31, is pivotally mounted within the trigger guard space by means of a pin 144 engaging a hole 145 of the trigger. The upper portion of the trigger within the casing is provided with a slot 146 in which the sear is adapted to move, and is provided at its upper end with a cross-pin 147 which interlockingly engages a notch 148 of the trigger control bar 149, shown in detail in Fig. 32. This trigger control bar has rectilinear sliding movement in a channel 150 provided in the casing and is limited in such movement by a pin 151 engaging a slot 152 of the bar. At its rear end the bar is provided with a shoulder 153 engaged forwardly of the tooth pawl 133 of the sear. A U-shaped trigger spring 154 positioned in the recess 125 of the trigger guard engages the inclined abutment surface 155 of the trigger, normally pressing the trigger in counterclockwise direction and the trigger control bar 149 rearwardly. Thus, clockwise movement of the trigger forces the trigger control bar forwardly, causing the sear to be swung in clockwise direction to release the hammer.

In the ordinary operation of the firearm, the sear 126 may have the pawl 133 fixedly associated therewith. However, the pawl 133 is preferably movably mounted so that it may yield forwardly in the event that the trigger is held back by the finger after firing with the trigger control bar 149 forwardly, while at the same time the bolt is opened and the hammer moved to cocked position with the sear in its hammer retaining position. In this case the trigger control bar, when released by disengagement of the finger from the trigger, will be permitted to move rearwardly into engagement behind the pawl, the pawl yielding to permit the shoulder 153 of the trigger control bar to move past it.

Above the trigger control bar 149 there is provided a hammer locking lever 156, shown in detail in Fig. 33, pivotally mounted by means of a pin 157 engaging a hole 158 in the lever. The rearwardly extending upper arm of this lever is provided with a contact end portion 159 disposed in the slot 62 of the casing, in position to be engaged and depressed by the lug 48 of the bolt in the locked position of the bolt, while its forwardly extending lower arm is provided at its end with a claw 160. This claw is in position to lockingly engage a notch 161 provided in the upper surface of the trigger control bar 149 in the open position of the bolt, as shown in Fig. 37, the claw being swung upwardly out of engagement with the notch in the closed and locked position of the bolt, as shown in Fig. 18. A helical spring 162 exerts downward pressure upon the claw end of the hammer locking lever to normally press the contact end 159 upwardly, this spring being positioned in a cylindrical passage formed by semi-cylindrical grooves 163 and 164 in the respective body portion 49 and cover portion 50 of the casing, a retaining screw 165 being screwed in a threaded hole 166 in the upper wall of the casing to retain the upper end of the spring. Engagement of the hammer locking lever with the trigger control bar, as shown in Fig. 37, prevents premature firing of the firearm at all times except when the bolt is in its fully closed locked firing position, as shown in Fig. 18.

Beneath the trigger control bar 149 there is provided a safety locking bar 167, shown in detail in Fig. 34, slidably engaged for rectilinear movement in a groove 168 of the casing, the

rearward end of this locking bar extending into the groove 146 of the trigger and being normally disposed in opposed spaced relation to the forward side of the sear 126. A safety lever 169, shown in detail in Fig. 35, is pivotally mounted at its upper end upon the pin 151, being provided at its upper end with a hole 170 for engagement with the pin. Below the hole 170 there is provided a slot 171 engaged by a pin 172 in the side surface of the safety locking bar 167, the lower end of the lever projecting into the exposed trigger guard space and being provided with a finger engaging end 173 for its convenient manipulation. Space is provided for the positioning of the safety lever beneath the cover plate 50 of the casing by providing a recess 174 in the trigger control bar 149, a recess 175 in the safety locking bar 167, a recess 176 in the outer edge surface of the trigger spring 154, and a recess 177 in the trigger guard. In the firing or release position of the safety lever it is disposed in its forward position, as shown in full lines in Fig. 18, the rearward end of the locking bar being spaced forwardly from the sear to permit its normal operation. In the safety locking position, the safety lever is moved rearwardly, as shown by the dot-and-dash lines in Fig. 18, where it is moved laterally into engagement with a locking notch 178, lateral pressure being exerted upon the lower end of the safety lever by a leaf spring 179 disposed in a pocket 180 provided at the inner side of the cover member 50. Thus, as the safety lever is moved rearwardly to the safety position, it automatically drops into the notch 178 under the pressure of the spring 179. In order to release it, the trigger finger is first pressed laterally against the end of the safety lever to disengage it from the notch 178, being then pressed forwardly to the releasing position, where it is frictionally retained by the pressure of the spring 179.

In Fig. 5 there is shown a gas accumulator attachment for the automatic opening of the bolt following each firing. This consists of a head 181 having a passage 182 in which the shouldered end portion 183 of the barrel 11 is engaged and secured by a cross-pin 184 engaging a groove 185 in the barrel. The barrel in this case is preferably shorter than the barrel of the manually operated or pump-action firearm, so that the overall length of the barrel and the head 181 will be substantially the same as the barrel of the manually operated firearm. Within the passage 182 there is engaged a pair of cup-shaped baffle members 186 and 187 respectively provided with orifice passages 188 and 189 in axial line with the bore of the barrel, these baffle members being secured by swedging the end surface of the head member over a shoulder 190 of the forward baffle member, as at 191. The arrangement is such that two expansion chambers are provided at the end of the barrel of substantially greater diameter than the bore of the barrel and of the passages 188 and 189, which correspond in diameter to the bore of the barrel. These expansion chambers are connected by vent ducts 192 and 193 to horizontal duct 194, the rearward end of which is in line with the end of a piston 195, slidably engaged in a cylinder 196 screwed at its forward end in the head member 191, and engaged at its rearward end in a passage 197 in the stock ferrule 108, the rearward end of the piston being engaged with an anvil formation 198 provided upon the forward end of the compression head member 66 of the action slide.

In order to permit the slide to be manually retracted, there is provided upon the underside of the member 66 a pivoted finger lug 199 adapted for movement in a slot 200 provided in the lower side of the stock. This finger is normally disposed in its raised inoperative position, as shown by the full lines, where it is releasably retained by a spring-pressed detent ball 201 disposed in a pocket 202 of the head member and engaging a recess 203 in the hub of the finger lug. In its operating position, the finger lug is swung downwardly, as shown by the dot-and-dash lines.

In operation the combined action of the firing gases and the bullet causes the compressed gases to be expanded in the expansion chambers and to flow into the vent ducts, forcing the piston rearwardly and moving the action slide to its retracted position to cause the bolt to automatically set the hammer in cocked position. The recoil spring 78 thereupon returns the action slide to its normal projected position. The increased diameter expansion chambers of the gas accumulator not only provide more effective pressure to retract the action slide, but have the advantageous effects of greatly reducing erosion and obstruction of the vent ducts and of reducing muzzle blast.

I have illustrated and described preferred and satisfactory embodiments of the invention, but it will be understood that changes may be made therein, within the spirit and scope thereof, as defined in the appended claims.

What is claimed is:

1. In a firearm, a barrel, a receiver fixedly secured to said barrel and having a bolt guide channel in axial line with said barrel including an upper wall and side walls and having a downwardly extending open chamber below said bolt guide channel, a unit removably engaged in said open chamber having a top wall constituting the base of said channel, a bolt engaged in said channel for rectilinear movement between forward closed and rearward open positions, said top wall of said unit having a horizontal rearward guide wall portion in downwardly spaced parallel relation to said upper wall which in cooperation with said upper wall and side walls guides said bolt in its rectilinear closing and opening movement and having a forward downwardly offset wall portion with respect to which said bolt in its forward closed position has transverse downward and upward movement respectively into locking and unlocking positions, said top wall of said unit having a transverse locking abutment portion between its forward and rearward wall portions adapted to be engaged by said bolt in its transversely moved locked position, and said bolt being downwardly removable from said channel through said chamber upon removal of said unit, and an action slide cooperatively connected to said bolt to impart transverse and rectilinear movement thereto.

2. In a firearm, a barrel, a receiver having a bolt guide channel in axial line with said barrel including an upper wall and side walls and having a downwardly extending open chamber below said bolt guide channel, a unit removably engaged in said open chamber having a top wall constituting the base of said channel, a bolt engaged in said channel for rectilinear movement between forward closed and rearward open positions, said channel having a rearward guide portion for guiding said bolt in its rectilinear closing and opening movement and having a forward locking portion relatively wider in a vertical direction

than said rearward portion wherein said bolt has up and down transverse unlocking and locking movement, a locking abutment carried by said top wall of said unit adapted to be engaged by said bolt in its downwardly moved locked position, said receiver having longitudinal slots in opposed side walls thereof, a rectilinearly movable action slide having side portions respectively engaged over said opposed side walls of said receiver, and bolt-actuating cam means connected to each of said side portions of said slide extending through said slots and cooperatively connected to the opposed sides of said bolt adapted through rectilinear movement of said slide to impart transverse and rectilinear movement to said bolt.

3. In a firearm, a barrel, a receiver having a bolt guide channel in axial line with said barrel including an upper wall and side walls and having a downwardly extending open chamber below said bolt guide channel, a unit removably engaged in said chamber having a top wall constituting the base of said channel, a bolt engaged in said channel for rectilinear movement between forward closed and rearward open positions, said channel having a rearward guide portion for guiding said bolt in its rectilinear closing and opening movement and having a forward locking portion relatively wider in a vertical direction than said rearward portion wherein said bolt has transverse unlocking and locking movement, a locking abutment carried by said top wall of said unit adapted to be engaged by said bolt in its transversely moved locked position, said receiver having longitudinal slots in opposed side walls thereof, an action slide having opposed sides engaged exteriorly over said side walls of said receiver for rectilinear movement thereon, pin and cam means respectively at opposed sides of said bolt extending through said slots and cooperatively connected to said bolt and said opposed sides of said slide adapted through rectilinear movement of said slide to impart transverse movement to said bolt in unlocking direction at the beginning of its retracting movement and in locking direction at the end of its projecting movement.

4. In a firearm, a barrel, a receiver fixed to said barrel having a bolt guide channel in axial line with said barrel and having a wall forming one side of said channel, a bolt engaged in said channel for rectilinear movement between forward closed and rearward open positions, and an action slide cooperatively connected to said bolt and engaged exteriorly of said receiver for rectilinear movement thereon between forward and rearward positions, said wall of said receiver having a cartridge ejection opening, said action slide having a wall slidably engaged with said wall of said receiver and including a solid closure portion engaged over and closing said cartridge ejection opening in the projected position of said action slide, and said wall of said action slide having a cartridge ejection opening forwardly of said solid portion and in rectilinear line with said cartridge ejection opening of said receiver adapted to register with said cartridge ejection opening of the receiver in the retracted position of the slide.

5. In a firearm, a barrel, a receiver fixed to said barrel having a bolt guide channel in axial line with said barrel including an upper wall and side walls and having a downwardly extending open chamber below said bolt guide channel, a unit removably engaged in said open chamber having a top wall constituting the base of said channel, the external upper and side surfaces

of said receiver being substantially in longitudinal flush relation with the adjacent external upper and side surfaces of said barrel, a bolt engaged in said channel for rectilinear movement between forward closed and rearward open positions, said top wall of said unit having a locking abutment with respect to which said bolt has transverse downward and upward movement respectively into locking and unlocking positions, and an action slide cooperatively connected to said bolt including a yoke member having upper and side portions engaged exteriorly of said external upper and side surfaces of said barrel and receiver for rectilinear movement thereon between forward and rearward positions, and a compression head portion connected to said side portions of said yoke member and disposed beneath said barrel and forwardly of said receiver, and recoil spring means disposed between said receiver and said compression head portion to impart projecting movement to said action slide.

6. In a firearm, a barrel, a receiver fixed to said barrel having a bolt guide channel in axial line with said barrel and having a wall forming a side of said channel, the external upper and side surfaces of said receiver being substantially in longitudinal flush relation with the adjacent external upper and side surfaces of said barrel, a bolt engaged in said channel of said receiver, an action slide cooperatively connected to said bolt including a yoke member having longitudinally extending upper and side portions engaged exteriorly of said external upper and side surfaces of said barrel and receiver for rectilinear movement thereon between forward and rearward positions, said wall of said receiver having a cartridge ejecting opening, one side portion of said yoke member being slidably engaged with said wall of said receiver and including a solid closure portion engaged over and closing said cartridge ejection opening in the projected position of said action slide, and having a cartridge ejection opening forwardly of said solid portion and in rectilinear line with said cartridge ejection opening of said receiver adapted to register with said car-

tridge ejection opening of the receiver in the retracted position of the slide, a pair of forwardly extending arms, one carried by each of said side portions, and a compression head portion connected to said arms and disposed beneath said barrel and forwardly of said receiver substantially medially between said arms, longitudinal guide means at each side of said receiver for sliding engagement by said yoke portion, and longitudinal guide means at each side of said barrel for sliding engagement by said compression head portion, said guide means of said receiver and said barrel each being open at their forward ends whereby said action slide is engageable therewith from the forward end of the firearm.

GEORGE F. GREBEY.
